UNITED STATES PATENT OFFICE.

EUGENE R. CARICHOFF, OF SCHENECTADY, NEW YORK, ASSIGNOR TO GENERAL ELECTRIC COMPANY, A CORPORATION OF NEW YORK.

ELECTROMAGNETIC SWITCH.

1,275,845.

Specification of Letters Patent. Patented Aug. 13, 1918.

Application filed September 25, 1916. Serial No. 121,966

To all whom it may concern:

Be it known that I, EUGENE R. CARICHOFF, a citizen of the United States, residing at Schenectady, county of Schenectady, State 5 of New York, have invented certain new and useful Improvements in Electromagnetic Switches, of which the following is a specification.

My invention relates to electromagnetic 10 switches for controlling electric circuits and more particularly to switches of this character which hold open when the current in a circuit is relatively high and closed when the current drops to a predetermined value.

15 In the starting of electric motors, it has been the practice to employ a plurality of electromagnetic switches which close successively to cut out sections of resistance from the motor circuit and bring the motor up to 20 speed. Various means have been devised for controlling the operation of the switches so that they will only close when the current is at a proper value, that is, after a switch has operated to cut out a section of resist- 25 ance the next switch will not operate until the current has dropped to a safe value due to the speeding up of the motor.

A form of switch which has frequently 30 been proposed for this purpose is one in which a shunt coil closes the switch and a series coil, instead of controlling the circuit of the shunt coil, positively prevents the switch from closing by actually holding it open, that is, the shunt coil pulls against the 35 series or "holding-out" coil. A switch of this general character is disclosed in patent to Fraser, #655,335. The difficulty with the device shown in this patent is that the value of current in the holding-out winding at 40 which the switch will close depends upon the pull of the shunt coil, which of course will vary with the voltage and also with the temperature of the coil. In other words, the "setting" of the switch, i. e. the motor 45 current value at which it closes, changes with change of voltage. It also closes at one value of current in the series coil when the shunt coil is cold and another when it is at its operating temperature which is ordi- 50 narily about 60 degrees C.

Attempts have been made to overcome this difficulty by having an auxiliary member, which is operated by the shunt coil, place a spring under tension which tends to move 55 the switch member to closed position. This

tendency is opposed by the series coil when the current is high and when the current drops to a predetermined value, the spring overcomes the pull of the series coil and closes the switch. Such an arrangement is 60 unsatisfactory for the reason that the switch is closed by a spring instead of by electro- 65 magnetic pull, and it is impossible to obtain the required pressure between the contacts. The spring weakens as the switch member moves toward closed position, and the press- 70 ing together of the contacts is accomplished when the spring is weakest. As the parts wear, the pressure between the contacts de- creases.

One of the objects of my invention is to 75 improve the electromagnetic switch of the type above described by providing means whereby the switch member will be operated so as to be positively closed and wiped home by the electromagnetic pull of the shunt coil 80 when the current in the series coil drops to a predetermined value, this being accom- plished by the use of an auxiliary member which is moved by the shunt coil to give the 85 switch member a bias or tendency to close, which bias or tendency is opposed by the series coil. The result of this arrangement is that the value of current in the series coil at which the switch closes will be independ- 90 ent of the variations in pull of the shunt coil due to variations in voltage and other causes and the switch will be closed and held closed magnetically.

In the accompanying drawing illustrating 95 one form of my invention, Figure 1 is a side elevation of a complete electromagnetic switch embodying my improvements; Fig. 2 is a front elevation of the same; and Figs. 3, 4 and 5 show in outline the various po- 100 sitions which the switch assumes in opera- tion.

Referring to Figs. 1 and 2, 10 represents an energizing winding which is shown as a fine wire winding suitable for use as a shunt 105 winding on an electromagnetic switch for controlling motor circuits. This winding is arranged to energize the magnetic structure composed of an upper pole piece 11 and a lower pole piece 12 connected by core 13. These parts, together with the winding 10 mounted upon the core, form an electromag- 110 net which is secured to an insulating base 14. A fixed contact 15 is also secured to the insulating base adjacent the magnet so as to

coöperate with the moving contact as hereinafter described. A switch member 16 is pivoted at 17 to the magnet frame. For this purpose a bracket 18, preferably of brass or other non-magnetic material, is secured to the pole piece 11. This bracket has arms 19 extending downward and outward from the pole piece. The switch member 16 is elongated in shape and pivoted near its middle portion so that one end extends downward to coöperate with the pole piece 12, while the other end extends upward toward the fixed contact 15. A contact 20 is mounted on the member 16 so as to coöperate with the fixed contact 15. These contacts are shaped so as to wipe or roll upon each other in a manner well known in the art and to this end the contact 20 is mounted upon a bracket 21 pivoted at 22, there being a compression spring 23 interposed between the bracket and a projecting lug 24 on the switch member 16. A tail piece 25 is provided for the bracket 21 for limiting the movement of the bracket in response to the pressure of spring 23. The lower end of the switch member forms an armature 26 which co-operates with the pole piece 12 and also with an auxiliary pole piece 27 which is secured to the pole piece 12 and bent around as shown, so that the magnetic circuit through the auxiliary pole piece is longer than that through the pole piece 12. The end of the switch member moves freely between the two pole pieces. The switch member, with the parts attached thereto, is so pivoted and weighted that it normally assumes the position shown in Fig. 1, that is, it is biased to the open position with the lower end separated from the pole piece 12 by the space 28.

Pivoted on the pivot 17 of the switch member, so as to move independently of the switch member, is a lever 29 of magnetic material. The upper end of this lever co-operates with the pole piece 11 so as to be magnetically attracted thereby while the lower end projects into the switch member 16, that is, it enters the space formed by the two webs of the member. Between the lower end of this lever 29 and the switch member proper is interposed a spring 30 which abuts against the adjusting screw 31. The arrangement is such that when the lever 29 is attracted by the pole piece 11 and the switch member 16 is held in its normal position shown in the drawing, the spring 30 is compressed so as to give the switch member 16 a tendency to rotate on its pivot and bring the contact 20 into engagement with contact 15. This tendency to move the switch member is increased by the magnetic attraction between the lower end of the switch member and the auxiliary pole piece 27.

The arrangement thus far described is substantially the same as that disclosed in

my previous application, Serial No. 870,807, filed Nov. 17, 1914, the principal distinction being, that while in my previous application the switch member in its normal position rests against the pole piece 12 with a non-magnetic stop interposed, in the present case, the member normally rests against a magnetic pole piece energized by the holding-out winding. It will be seen, therefore, that the switch of my previous application may be utilized either as a single winding contactor of the lock-out type, or, by the addition of the parts hereinafter described, may be utilized as a compound contactor, that is, one having a shunt operating winding and a series holding-out winding.

Secured to the insulating base below the magnetic structure just described is an electromagnet comprising a U-shaped pole piece 32 inclosing a magnetizing winding 33. This winding it will be observed is a heavy or coarse winding of a type suitable for carrying the motor current where the switch is used for controlling an electric motor. This winding is shown as being divided into two parts, this being for the purpose of strongly holding the switch member in open position with a large number of turns until it is desired that the switch shall be under the control of the motor current whereupon a part of the turns will be cut out. Secured to the lower end of the switch member 16 by screws 34, is an arm 35, which projects downward toward the pole piece 32. Secured to the lower end of this arm is an armature 36 which co-operates with the pole piece 32. This armature is adjustable upon the arm 35 by means of a screw 37, the armature having a knurled edge engaged by a latching member 38, which holds the armature in any position to which it may be turned. By means of the screw 37 the armature 36 may be so positioned that it is equally attracted by the pole piece on either side of it so that the magnetic forces acting on either side of the armature 36 are substantially balanced. When the winding 33 is sufficiently energized, the pole piece 32 attracts the armature 36 and thus holds the switch member in open position.

As thus constructed and arranged, the operation of this switch is as follows: Assuming that the winding 10 is energized by being connected across a circuit which is of substantially constant potential, and the winding 33, either as a whole or in part, connected to a circuit in which the current is variable, as for instance in the armature circuit of an electric motor, if the current in the circuit to which this winding is connected is of such a value that the switch should not close, the switch member will be held open and the parts will assume the position shown in Fig. 4. It will be noted by reference to Figs. 1 and 3 that the only thing that

has happened, that is, the only part that has moved is the lever 29 which has moved up to the pole piece 11 due to the energization of the winding 10, and has compressed the 5 spring 30. The tension of this spring now gives the switch member a tendency to close, which tendency is opposed by the pole piece 32, the pull of which is due to the energization 10 of the winding 33. There is also a pull across the gap 28 which, however, is of no importance in this connection since the gap is so adjusted that the tension of the spring, together with the pull of the auxiliary pole piece 27, will preponderate and cause the 15 switch to close when the current in the winding 33 drops to a predetermined value. The value of current at which the switch will close may be adjusted by adjusting the armature 36 on its screw so as to vary the air 20 gap between it and the pole piece 32. When the current in the winding 32 drops to the predetermined value, at which it is desired that the switch shall close, the constant force due to the tension of the spring 30, together 25 with the magnetic pull of the pole piece 27, which will vary somewhat due to the variations in voltage upon the coil 10, and the heating of the coil will overcome the pull of the pole piece 32, and the switch parts 30 will move to the position shown in Fig. 5.

It will be noted, however, that while the pull of the pole piece 27 varies due to variations in voltage and heating of the coil 10, this variation will not substantially vary the 35 point at which the switch will close, because it is offset by variations in pull across the air gap 28, since the pull in these two air gaps varies at the same rate. The effective force which tends to move the switch toward 40 closed position therefore, will be substantially the constant force of the spring tending to close the switch opposed by the variable magnetic force due to the winding 33. The switch will, therefore, always close at a 45 definite value of current in the winding 33 regardless of any variations of magnetizing force due to the winding 10.

While I have described my invention as embodied in concrete form and as operating 50 in a specific manner in accordance with the provisions of the patent statutes, it should be understood that my invention is not limited thereto, since various modifications thereof will suggest themselves to those 55 skilled in the art without departing from the spirit of my invention, the scope of which is set forth in the annexed claims.

What I claim as new and desire to secure by Letters Patent of the United States, is,—

60 1. An electromagnetic switch comprising an energizing winding and a magnetic structure therefor, a switch arm normally in open position and held in closed position by a direct magnetic pull thereon set up by said winding, a member moved by the said wind-

ing to set up a force in a direction to move the switch arm to closed position, and a holding-out winding for preventing the force from becoming effective to move the switch arm in a closing direction until the 70 current in said holding-out winding drops to a predetermined value.

2. An electromagnetic switch comprising an energizing winding and a magnetic structure therefor, a switch arm normally in open 75 position and held in closed position by a direct magnetic pull thereon set up by said winding, a holding-out winding, and a member moved by the energizing winding against a constant force, which reacts on the switch 80 arm to move it in a closing direction when the current in said winding drops to a predetermined value.

3. An electromagnetic switch comprising an energizing winding and a magnetic structure 85 therefor, a switch arm normally in open position and held in closed position by a direct magnetic pull thereon set up by said winding, a member moved by the winding to apply a constant force tending to move 90 the switch arm to closed position, and a holding-out winding for holding the switch arm in open position until the current in said holding-out winding drops to a predetermined value.

95 4. An electromagnetic switch comprising an energizing winding and a magnetic structure therefor, a switch arm normally in open position and held in closed position by a direct magnetic pull thereon set up by said 100 winding, a member moved by the winding to apply a constant force to said switch arm in a direction to close the switch arm, and a holding-out winding for holding the switch arm against the constant force until 105 the current in said holding-out winding drops to a predetermined value.

5. An electromagnetic switch comprising an energizing winding and a magnetic structure 110 therefor, a pivoted switch arm normally in open position and held in closed position by a magnetic force set up by said winding acting on one side of the pivot, a holding-out winding acting on the same side of the pivot to hold the switch arm in open position, and a member moved by the energizing winding to set up a force which becomes effective to move the switch member in a closing direction when the current in the holding-out winding drops to a 120 predetermined value.

115 6. An electromagnetic switch comprising an energizing winding and a magnetic structure therefor, a pivoted switch arm normally in open position and held in closed 125 position by a magnetic force set up by said winding acting on one side of the pivot, a holding-out winding acting on the same side of the pivot to hold the switch arm in open position, and a member moved by the mag-

4
netic force of said energizing winding acting on the other side of the pivot to set up a constant force which becomes effective to move the switch member in a closing direction when the current in the holding-out winding drops to a predetermined value.

7. An electromagnetic switch comprising an energizing winding and a magnetic structure therefor, a switch arm normally in open position and acted upon by a force set up by said winding tending to move it to closed position and a counteracting force set up by said winding which substantially balances the arm magnetically, a holding-out winding for holding the switch arm in open position, and a member moved by the energizing winding against a constant force which reacts on the switch arm to move it out of balance so that the closing force prevails to close the switch when the current in the holding-out winding drops to a predetermined value.

8. An electromagnetic switch comprising an energizing winding and a magnetic structure therefor, a switch arm normally in open position and held in closed position by a direct magnetic pull thereon set up by said winding, a spring, a member moved by said

winding to place said spring under strain and set up a force in a direction to move the switch arm to closed position and a holding-out winding for preventing the force from becoming effective to move the switch arm in a closing direction until the current in said holding-out winding drops to a predetermined value.

9. An electromagnetic switch comprising an energizing winding and a magnetic structure therefor, a switch arm normally in open position and acted upon by a force set up by said winding tending to move it to closed position, and a counter-acting force set up by said winding which substantially balances the arm magnetically, a holding-out winding for holding the switch arm in open position, a spring, and a member moved by the energizing winding to place said spring under strain to cause it to react on the switch arm to move it out of balance so that the closing force prevails to close the switch when the current in the holding-out winding drops to a predetermined value.

In witness whereof, I have hereunto set my hand this 23rd day of September, 1916.

EUGENE R. CARICHOFF.
